United States Patent Office.

JOHN MURPHY, OF BRANDON, VERMONT.

Letters Patent No. 61,557, dated January 29, 1867.

IMPROVED COMPOSITION FOR POLISHING STOVES.

The Schedule referred to in these Letters Patent and making part of the same.

TO ALL WHOM IT MAY CONCERN:

Be it known that I, JOHN MURPHY, of Brandon, in the county of Rutland, and State of Vermont, have invented, discovered, and produced a new and original compound or composition for polishing stoves, stove pipes, iron grates, &c., &c.; which I have denominated "Liquid Lightning Stove Polish," and which I verily believe has not been known or used prior to the production thereof by myself; and I do hereby declare that the following is a full and exact description of the manner in which I compound and manufacture the same:

To a given quantity, say seven pounds, of either black lead, silver lead, or carbonate of iron, add three pints of molasses, or its equivalent in other saccharine matter, one gill of muriate of tin or zinc, and nine quarts of water; mix and shake together.

The polish may be applied to the stove with an ordinary paint brush. The stove may be either warm or cold. When dry, rub with dry brush or broom or cloth, and a beautiful and durable polish and lustre will almost instantaneously appear. Neither dust nor smell will be perceptible.

What I claim as my invention, discovery, and production, and desire to secure by Letters Patent, is—

The combination of the ingredients above named, as well in the proportions specified, as also in any and all other proportions, and in greater or less quantities.

I also claim the right of substituting and using any other compound made substantially of the same materials hereinbefore specified, though known by any other name.

JOHN MURPHY.
